UNITED STATES PATENT OFFICE

141,027

DESIGN FOR A TOY AIRPLANE

Norma M. Soulé, Evanston, Ill.

Application March 3, 1945, Serial No. 118,248

Term of patent 14 years

(Cl. D34—15)

To all whom it may concern:

Be it known that I, Norma M. Soulé, a citizen of the United States, residing at Evanston, in the county of Cook and State of Illinois, have invented a new, original, and ornamental Design for Toy Airplane, of which the following is a specification, reference being had to the accompanying drawing, forming part thereof:

Figure 1 is a top plan view of a toy airplane, showing my new design.

Fig. 2 is a front elevation of the same.

Fig. 3 is a side elevational view thereof.

I claim:

The ornamental design for a toy airplane, as shown.

NORMA M. SOULÉ.
